CLAIM

The ornamental design for a game console, as shown and described.

DESCRIPTION

FIG. 1 is a front, top, and right perspective view of a game console, comprising a main body member and a detachable top, showing my new design with the top component removed for complete disclosure;

FIG. 2 is a front, top, and right perspective view showing the game console with the top component attached to the main component;

FIG. 3 is a front exploded view thereof;

FIG. 4 is a front view of FIG. 1;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings illustrate the portions of the game console, which form no part of the claimed design.
